(57) **CLAIM**

The ornamental design for a swimming pool sweeper brush, as shown and described.

DESCRIPTION

FIG. 1 is a front perspective view of the swimming pool sweeper brush;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the drawings illustrate portions of the swimming pool sweeper brush that form no part of the claimed design.

The swimming pool sweeper brush is shown with a symbolic break in its length. The appearance of any portion of the article beyond the break lines forms no part of the claimed design.
